UNITED STATES PATENT OFFICE.

OLOF A. ECKRE, OF KINDRED, NORTH DAKOTA.

CARPENTER'S COMBINATION-TOOL.

1,134,826.

Specification of Letters Patent.

Patented Apr. 6, 1915.

Application filed August 15, 1914. Serial No. 856,972.

To all whom it may concern:

Be it known that I, OLOF A. ECKRE, residing at Kindred, in the county of Cass and State of North Dakota, have invented a new and Improved Carpenter's Combination-Tool, of which the following is a specification.

This invention is in the nature of an improved tool or implement more especially designed for carpenters' uses, and in which the several parts are so combined and adapted for adjustment to provide, as it were, a number of different tools or devices such as are usually required for carpenters' uses, and my said invention primarily has for its object to provide a combination tool or implement of the general character stated, of a simple and economical construction, in which the several parts are arranged for being conveniently adjusted for their various uses and the said several parts coöperatively so formed and combined that they can be compactly folded to permit of readily carrying said tool in the pocket.

With other objects in view that will hereinafter appear my invention is in the nature of a new and improved combination tool that embodies the peculiar features of construction and novel arrangement of the parts hereinafter fully explained, specifically pointed out in the appended claims and illustrated in the accompanying drawings in which:

Figure 1 is a perspective view of my improved tool, the same being shown in its folded position. Fig. 2 is a similar view that shows the device used as dividers. Fig. 3 is a longitudinal section thereof, the parts being adjusted to form a "try square." Figs. 4 and 5 are cross sections taken on the lines 4-4 and 5-5 on Fig. 1. Fig. 6 is a detail view of one corner of the main or body member.

In the practical arrangement, my invention comprises a metallic body that includes an arm 1 that has a longitudinally extending socket 10 formed between the outer or scale member 12, and an upper or guide member 13, the latter being bent upwardly at right angles to the member 12 to form a combined stiffener and abutment 12^a that constitutes the inner edge of a flat or base member 14 that extends laterally from the member 12 and whose outer edge 16 merges with an inturned angle portion 18 of the scale bar, and which forms a part of the

edge 17 of a try square, when the pivoted blade 22, presently referred to, is swung to the position shown in Fig. 3.

18 designates a bifurcated arm that is 60 horizontally disposed, relatively to the arm 1, and extends in parallelism therewith, as is clearly shown in Fig. 1, to provide an open guideway *a* that is used as a gage for chair rails, baseboards and the like. Arm 65 18 has a number of lateral gage flanges and at one side between a pair of the said flanges it carries a horizontally disposed spirit level 21. 21^a denotes a vertically disposed spirit level located at the inner end of the arm 18, 70 the outer end of which terminates in a divider point 18^a, as shown. The arm 18 has a vertical socket 23, that extends the full length thereof and at one end the said socket continues through the base portion 14, as is 75 clearly shown in Fig. 6.

A blade 22 is pivotally mounted on a thumb screw stud 24 that passes through the base portion 14 and the said blade, when folded down, closes into the socket 23, and 80 the said blade which is of a length equal that of the arm 18 has a divider point 22^a for coöperating with the point 18^a when the blade is swung out as shown in Fig. 2, which shows the tool used as a divider. The pivoted end of the blade is of substantially circular shape, and the outer edge of the base member 14 is likewise curved to provide a smooth curved edge when the blade 22 is turned to any of its positions other than a 90 right angle to the arm 18. By connecting the blade 22 to the arm 18 in the manner stated and shown it is obvious that the implement may be readily used as a divider by pulling out the blade, as shown in Fig. 95 2, and when the said blade is turned out at right angles to the arm 18, as shown in Fig. 3, the tool or implement is adapted for use as a try square, it being also apparent that by shifting the blade 22 to any of its intermediate positions, the same is useful as a bevel square.

The scale bar or member of the arm 1 has a longitudinal slot 11 in which are slidably mounted clamping screws 25-26, one of 105 which passes through the inner portion of a gage 27, slidably mounted on the member 12 on which it is adjustably secured by a thumb nut 28 that engages the screw 25 (see Fig. 5). The gage 27 which is in the nature 110 of a hollow casing has its opposite sides 27^a inclined on an angle of forty-five degrees.

30 designates a square shaped gage, removably secured to slide on the member 12 on which it is held by a thumb screw 31 that engages the screw 26 and the said gage 30, 5 in connection with the gage 27, constitutes means for gaging clap boards. Each of the opposite ends of the member 12 has a marking stud 32, as shown.

From the foregoing taken in connection 10 with the drawing, the complete constructions, the manner in which my device is used and its advantages will be readily understood.

What I claim is:

- 15 1. A tool comprising a base member and two parallel arms, one of said arms including a pair of parallelly disposed flanges spaced apart, one of said flanges terminating short of the other flange at the base member 20 and extending at right angles to the other arm to form a gage stop and stiffening member, said other arm having additional gage stops and stiffening members paralleling said first mentioned gage stop and spaced 25 apart substantially as shown and described.
2. A tool comprising a base member and two parallel arms, one of said arms including a pair of parallelly disposed flanges spaced apart, one of said flanges terminating 30 short of the other flange at the base member and extending at right angles to the other arm to form a gage stop and stiffening member, said other arm having additional gage stops and stiffening members 35 paralleling said first mentioned gage stop and spaced apart, said second mentioned arm having a longitudinal groove in its edge and a blade adapted to be folded into said groove, and an adjustable hinge connection 40 between said blade and said base member,

said hinge connection including a wing nut, said lateral flanges and stops terminating in a plane parallel to the plane containing said second mentioned arm and at a distance greater than the depth of said wing nut 45 whereby when said tool is laid down on a support, with the wing nut side lowermost, said tool will lie without rocking and serve as a straight edge.

3. A tool of the character stated comprising a main or body portion having an arm composed of a pair of spaced members joined at one end, a base portion that projects laterally from the said arm, one member of the said arm being curved outwardly 50 to form a vertical edge flange connected with the base portion, and an arm that extends from the base member and is disposed in parallelism with the other arm and spaced from said other arm. 55

4. A tool of the character stated comprising a main or body portion having an arm composed of a pair of spaced members joined at one end, a base portion that projects laterally from the said arm, one member of the said arm being curved outwardly 60 to form a vertical edge flange connected with the base member, an arm that extends from the base portion and is disposed in parallelism with the other arm, the said first mentioned arm having one of its members provided with a longitudinal slot, clamp screws 65 slidably mounted in the said slot and gage members on said slotted member detachably connected with the said clamping screws. 70

OLOF A. ECKRE.
